UNITED STATES PATENT OFFICE.

JOHN B. PERRY, OF EDMONDS, WASHINGTON.

CONVERTIBLE FURNITURE.

1,258,141.

Specification of Letters Patent.

Patented Mar. 5, 1918.

Application filed September 18, 1917. Serial No. 191,936.

To all whom it may concern:

Be it known that I, JOHN B. PERRY, citizen of the United States, residing at Edmonds, in the county of Snohomish and 5 State of Washington, have invented certain new and useful Improvements in Convertible Furniture, of which the following is a specification.

This invention relates to convertible furniture; and its object is to produce a piece 10 of furniture which is adapted to be employed as a comfortable armchair, a couch, a lounge, a full-length bed or a dining table. The invention consists in the novel construction, adaptation and combination of 15 parts as will be hereinafter described and claimed.

My invention is illustrated in the accompanying drawings, in which—

20 Figure 1 is a perspective view of the invention as it appears in the form of a bed. Fig. 2 is a side elevation of the invention shown as an arm chair. Fig. 3 is a transverse section through 3—3 of Fig. 2. Fig. 4 25 is a side elevation of the invention as a dining table. Fig. 5 is a plan view of Fig. 4, shown partly in section. Fig. 6 is a side elevation of the invention in the form of a settee. Fig. 7 is a side elevational view with 30 the parts arranged in compact form for storage or transportation. Figs. 8 and 9 are fragmentary perspective views of furniture members to illustrate complementary coupling devices.

35 Referring particularly to Figs. 2 and 3, illustrating the invention in the form of a chair, there is a seat frame 10 supported by legs in the nature of corner posts 11 and 12 of which those at one side, as 12, are preferably extended above the frame 10 and serve with the associated rail 13 to afford the left-hand arm A of the chair. The other arm B of the chair is formed of top and bottom rails 14 and 15 connected by upright 40 post elements 16 arranged to be coextensive with the aforesaid legs 12 when the referred to arm is secured to said frame seat as represented in Figs. 2 and 3, by means of dowel pins 17 and a hook 18 on the arm engaging 45 a stud 19 on the subjacent leg.

The inner sides of the respective arms are closed by walls 20 which are desirably upholstered as indicated by 21. The outer sides of said arms are closed by doors 22 to 50 give access to compartments 23 within the

respective arms. 24 represents upholstering for the seat frame and below the latter is a compartment for the reception of drawers 25. Secured to the sides of the seat frame are guides 26 to accommodate two-part bars 27—27¹ pivotally connected by pins, such as 28, the rearmost bar parts 27 being pivotally connected by pins, such as 29, to the lower end of a back C having its front upholstered, as at 30 and a plane rear surface 31.

60 Hooks as 32, connected to the chair arms and engageable with studs 33 on the back serve to retain the same in upright or inclined positions. Attachments 34 and 35 may be used interchangeably for head and 65 foot rests upon the chair back and in front of the legs as shown in Figs. 2 and 3.

The outer edges 34² and 35² of said attachments are desirably formed of arcuate shapes to improve their appearance in a 70 chair and also to harmonize with the co-operating parts when utilized in a table top as will be presently explained.

75 For detachably connecting said attachments to the back and legs I provide on the former headed pins 36 protruding from elements 37 of hinges 38, Fig. 8, which are secured to the attachments, said pins being engageable in key-hole shaped slots 39, Fig. 9, provided in plates 40 secured to the chair 85 back, the seat frame 10 and the front legs respectively.

To convert the device into a table as shown in Figs. 4 and 5, the bars 27—27¹ are withdrawn sufficiently from the guides 26 to 90 enable the bar parts 27, one on each side, to be turned up as represented in Fig. 4 to allow the member C, which in the chair constitutes the back, to be laid upon the arm rails as illustrated and become the central 95 portion of the table top. To the ends of the member C are connected the attachments 34 and 35 and to each side thereof are secured segmental pieces 42 and 43 by means of dowels 44 on the latter engaging in holes 100 44¹ (shown in Figs. 1, 2 and 6); the adjacent segmental pieces being coupled by dowels 44² as indicated by dotted lines in Fig. 5.

The above named parts comprising the 105 table top when assembled afford a plane upper surface by the provision of rabbets such as C¹, 34¹ and 35¹ in the sides of the member C and said attachments to receive the edges 42¹ and 43¹ of the respective segmental 110

pieces. Thus connected the interfitting parts of the table top contribute to afford a rigid structure of a substantially circular form, the same being held down upon the supporting arms by the bar parts 27 at the rear and hooks 45 at the front which engage studs 45¹ provided on the respective arms.

To employ the device as a settee, see Fig. 6, the bar parts 27-27¹ are adjustably moved 10 into the positions as indicated in the view, the member C is then swung to be in alignment with the seat, the attachments 34 and 35 respectively connected to the member C and seat frame, as shown, the arm B transferred from the side of the seat to the opposite side of the member C to which it is connected by the dowels 17 engaging in holes such as 46 (Fig. 3) provided in said member. In the embodiment shown a supplementary or filling element 47 is introduced to fill the space between the parts A and B to furnish a continuous back to the settee. As will be seen from an inspection of Fig. 6, one end of the member C is supported by its hinged connection with the bars which in turn, are supported from the seat frame 10 through the instrumentality of the guides 26, while the outer end of said member is supported upon segmental pieces 42 arranged transversely, as best shown in Fig. 1, and connected thereto by the aforesaid dowels 44² engaging in suitably located holes (not shown) provided in the member C. In this adaptation of the device, 35 the segmental pieces 43 may advantageously be employed to serve as braces for the segmental pieces 42 which are being used as legs, and under such conditions the dowels 44 of pieces 43 engage in holes 44³ therefor 40 provided in member C and a dowel 44⁴ provided in each of the pieces 42 engages in a hole 44⁵ provided in the adjacent end of a piece 43. To convert the device into a full length bed all of the parts remain as above 45 explained except that the attachments 34 and 35 are turned down to occupy the positions in which they are represented in Fig. 1. In Fig. 7 is shown how the device may be packed into a small and substantially cubical shape for storage or transportation.

The construction and manner of regulating the device to serve in the various appli-

cations will, it is thought, be understood from the foregoing description.

The advantages of the invention reside 55 principally in its simplicity, and wide range of usefulness.

What I claim, is—

1. In an article of furniture, the combination with the chair seat and a support therefor, of a member operatively connected therewith and adapted to be used in inverted horizontal positions to respectively serve as a table-top element or a bed element and means associated with said member and adapted to be interchangeably used as table-top elements or as leg supports for said member when the latter is utilized as a bed element.

2. In an article of furniture, a seat frame, 70 posts supporting the same, the posts on one side of said frame extending above the latter, a rail secured to the upper ends of said such post extensions and constituting therewith an arm of a chair, another arm detachably connected to said frame, a back-member, means connecting said back-member to said frame whereby it may be selectively employed either as a chair back, a table-top, or 75 a seat element of a settee.

3. In an article of furniture, a seat frame, a support therefor, arms for said seat frame, a back member, means to connect said member to the seat frame whereby it may be utilized as a chair back at the rear of said frame or as a table-top upon the chair arms, means for securing said member in adjusted positions when utilized as a chair back, and means to secure the member upon said arms 85 when used as a table-top.

4. In an article of furniture, the combination with a chair frame comprising seat, leg and arm elements, of a back-member secured to said frame and means including jointed-bars for connecting said back-member to the chair frame whereby the back-member is adapted to be used as a table-top or a bed element selectively.

Signed at Seattle, Washington, this 8th day of September, 1917.

JOHN B. PERRY.
